Byron Stetton Parmenter

UNITED STATES PATENT OFFICE.

JOSEPH E. FALCK, OF PITTSBURGH, PENNSYLVANIA, ASSIGNOR TO NATIONAL CASKET COMPANY, INCORPORATED, OF PITTSBURGH, PENNSYLVANIA, A CORPORATION OF NEW YORK.

CASKET HANDLE.

Application filed July 22, 1927. Serial No. 207,729.

This invention relates to casket handles and particularly to a handle which may be constructed at low cost, has ample strength and presents a neat appearance as is required for articles of this character.

Casket handles as heretofore constructed have generally comprised an attachment plate having spaced apart hinged members thereon. The hinged members have openings formed therethrough to accommodate a grip member, this last being held in place by set screws in the hinge portions. The various parts are generally plated, polished and lacquered before assembly and difficulty is usually experienced in putting the grip member in place. The lacquer and the plating are scored and scratched, frequently necessitating re-finishing.

I provide a handle comprising a supporting member, a grip member and a retainer lying across the grip member and permanently engaging the supporting member on opposite sides of the grip member so as to hold the grip member in place. The retainer preferably comprises a strip of wrought metal arranged to make a snap connection with the supporting member. The supporting member is preferably made of wrought metal having a cast reinforcement and the retainer is made spring-like so as to snap over hooks formed in the wrought metal portion of the supporting member. The retainer is so constructed that a portion thereof may be permanently deformed so as to lock it in place.

In the accompanying drawings which illustrate the present preferred embodiment of the invention, Figure 1 is a front elevation of a casket handle;

Figure 2 is a vertical transverse section taken on the line II—II of Fig. 1;

Figure 3 is a horizontal section taken on the line III—III of Fig. 1; and

Figure 4 is a perspective view of the retainer.

In the illustrated embodiment of the invention there is shown a handle comprising a plate 2 adapted to be attached to the casket, hinge members 3 and a grip member 4. The hinge members 3 are pivoted on the plate 2 by pins 5. The handle normally lies against the casket but may be swung outwardly therefrom when the handle is to be used. Each hinge or supporting member

3 is shouldered as indicated at 6 so as to limit the outward movement.

Each hinge member 3 is formed of a portion 7 stamped from sheet metal and having a die cast reinforcement 8. The sheet metal portion extends throughout the entire hinge portion so that the pin 5 passes therethrough. The hinge member is provided with arms 9 and 10 forming a recess which receives the grip member 4. The portions of the stamped member 7 which extend into the arms 9 and 10 terminate in hooks 11.

A retainer 12 extends across the open side of the recess in the hinged member and engages the hooks 11 so as to hold the grip member 4 in place. The retainer 12 is made of wrought metal and is provided with slots 13 at each end to accommodate the hooks 11. The retainer possesses sufficient spring so that it may be forced over the hooks 11 and make a snap connection.

The retainer 12 is further provided with a loop portion 14. The retainer is originally formed as shown in Fig. 4 and after the handle has been assembled the loops 14 are permanently deformed as indicated at 14^a in Fig. 2. The deformation of the loop 14 serves to permanently connect the handle parts together. It will be noted from Fig. 2 that the retainers 12 lie against the casket when the hinge members are in the position of rest, and that they are on the under side of the handle and out of view when the hinge members are swung outwardly.

The crimping of the retainer 12 is effective not only for permanently securing it in place but also for causing the arms 9 and 10 of the hinge member to tightly clamp the grip member 4 and prevent relative movement.

There is no necessity for sliding the hinge members and the grip members along one another during the assembling operation as the grip member may be fitted directly into the open sided recess. Scratching or marring of the finish is thereby avoided and, at the same time, a strong and neat handle is secured.

I have illustrated a preferred form of the invention. It will be understood, however, that it is not limited to the form shown as it may be otherwise embodied within the scope of the following claims.

I claim:

1. A casket handle comprising a support-

- ing member having a recess formed there-
in, a grip member fitting in the recess and
a spring member extending across the re-
cess and adapted for being sprung into en-
gagement with the supporting member so
as to hold the grip member in place.
2. A casket handle comprising a support-
ing member, a grip member and a retainer
lying across the grip member and perma-
nently engaging the supporting member on
different sides of the grip member so as to
hold the grip member in place, the retainer
making a snap connection with the support-
ing member.
3. A casket handle comprising a support-
ing member having spaced apart hook por-

tions, a grip member lying between the hook
portions and a retainer extending from one
hook portion to the other and effective for
holding the grip member in place.

20

4. A casket handle comprising a support-
ing member having spaced apart hook por-
tions, a grip member lying between the hook
portions and a retainer extending from one
hook portion to the other and effective for
holding the grip member in place, the re-
tainer having a portion adapted to be per-
manently deformed so as to permanently se-
cure the parts together.

25

In testimony whereof I have hereunto set 30
my hand.

JOSEPH E. FALCK.
